UNITED STATES PATENT OFFICE.

HENRY E. PRIDMORE AND WILLIAM R. BAKER, OF CHICAGO, ILLINOIS,
ASSIGNORS TO THE MCCORMICK HARVESTING MACHINE COMPANY,
OF SAME PLACE.

HARVESTER.

SPECIFICATION forming part of Letters Patent No. 412,543, dated December 9, 1890.

Application filed March 8, 1887. Serial No. 230,076. (No model.) Patented in England June 8, 1886, No. 7,693.

To all whom it may concern:

Be it known that we, HENRY E. PRIDMORE and WILLIAM R. BAKER, citizens of the United States, residing at Chicago, in the county of Cook and State of Illinois, have invented certain new and useful Improvements in Harvesters, (for which Letters Patent of the Kingdom of Great Britain, No. 7,693, were granted, with our knowledge and consent, on the 8th day of June, 1886,) of which the following is a specification.

An application was filed in the Patent Office of the United States on the 10th day of July, 1886, Serial No. 207,666, by ourselves for Letters Patent for an improvement in harvester-frames. In such application the sills and girts of the elevator-frame were described as formed of square pipe, or, in other words, of tubes of rolled or forged metal, rectangular in cross-section; but the rear platform-sill was retained in the old and cumbrous wooden form. One feature of the present invention consists in constructing this latter sill, and also the divider-girt, of square pipe, and in accessory devices for uniting the divider-girt to the angle-iron finger-bar and to the divider-board, and also for protecting the grain-wheel.

A further feature of the invention relates to the tightener for the platform-apron, and yet other features relate to the mounting of the inner roller of the platform-apron and to the supporting of the rear end of the seat-plank over the elevator.

In the drawings, Figure 1 is a top plan view of a machine embodying our invention, the platform-apron being removed to expose the tightener. Fig. 2 is a rear elevation of said machine; Fig. 3, an elevation from the divider end; Figs. 4 and 5, enlarged details in side and rear elevation, respectively, of the joint between the finger-bar and divider-girt; Figs. 6, 7 and 8, enlarged details in top plan view and side and rear elevation, respectively, of the rear or false shoe which bridges the space between the outside guard-finger and the divider-girt; Fig. 9, an enlarged detail of the joint between the divider-girt and rear sill of the platform-frame; Fig. 10, an enlarged detail of the platform in vertical trans-

verse section through the rear part thereof, 50 showing the tool-box; Figs. 11 and 12, enlarged details in side and rear elevation, respectively, of the joint between the rear platform-sill, rear elevator-sill, and one of the cross-girts of the elevator-frame; Figs. 13 and 55 14, enlarged details of the bearing for the rear gudgeon of the inner platform apron-roller and fastening-plate for the foot of the rear inner elevator-strut; Figs. 15 and 16, enlarged details in plan and section of the actuating parts of the apron-tightener; Figs. 17, 60 18, and 19, enlarged details in plan, cross-section, and side elevation of the bearing-box for the movable apron-roller; Fig. 20, an enlarged detail in side elevation of the grain-wheel bracket or rack-standard mounted upon the divider-girt; Fig. 21, a horizontal section therethrough, showing also the grain-wheel on the correspondingly-numbered line in the preceding figure; Fig. 22, a vertical section, 65 70 and Fig. 23 a horizontal section, as likewise indicated by numbered lines; and Fig. 24, a rear elevation thereof.

Now, proceeding to describe the invention, the front sill A of the platform-frame is or may 75 be a bar of wood, as usual, forming a back to an angle-iron finger-bar A', which has its horizontal web a uppermost and flush with the upper edge of said sill, and, being bolted thereto at intervals, strengthens and braces 80 it. The front sill is overlaid by a wooden strip A² to close the space beneath the upper 85 ply or surface of the platform-apron when this is higher than the finger-bar. The rear sill B, as already intimated, is to be constructed as a square pipe or tubular bar of rolled or forged iron, rectangular in cross-section, occupying the place of the customary wooden rear platform-sill. At its outer or grain end this sill receives a metal bracket 90 or spacing-block B', having snugs b at its foot, whereby it saddles and closely embraces the upper side of the sill, and at its top a slightly-oblique seat b' for the rear end of the divider-girt C, which likewise is a rectangular tubular bar and is secured at this point by a bolt c, passing through the bracket and rear sill, thence extends forwardly past the 95

finger-bar and to the point of the divider, being suitably supported adjacent to the finger-bar by an upright or standard therefrom. To the inner side of the tubular rear sill, or 5 to brackets c' seated thereon, is bolted a wooden bar C' , to which the bottom boards of the platform may be attached, and somewhat in advance of this bar is a parallel plank or board C^2 , placed on edge along said bottom 10 boards, which supports the rear guide-bar c^2 for the platform-apron, the front guide-bar c^3 being secured to the front sill in the usual way. The space between the plank and the rear sill may be covered by a lid C^3 , 15 hinged to said plank, and thus form a toolbox, and this lid may at any time be turned up to act as a shield or wind-board for the rear of the apron.

Overlapping the rear sill of the platform-frame at its stubble end and on its upper side 20 is the rear sill D of the elevator-frame, also formed as a square pipe or hollow bar of rolled or forged iron rectangular in cross-section, and it may be here stated that all of the 25 sills or girts hereinafter mentioned are of similar form and structure, except that the girts will ordinarily be of less diameter than the sills.

When a wooden rear sill is used for the 30 platform-frame, it is of such height as to come up against the rear elevator-sill and be bolted directly thereto, but the tubular sill will be ordinarily low down, and for a reason presently given it is often necessary to have the 35 elevator-sill considerably higher. Therefore spacing brackets or lifts D' of metal will be employed between the two sills where they overlap. Two of these brackets are employed, both having snugs d to embrace the platform- 40 sill and seats d' for the reception of the elevator-sill, one being located at the stubble end of the platform-sill and the other at the inner or grain end of the elevator-sill, and bolts d^2 passing through the two sills and 45 brackets complete the joint. The brackets are also offset at one side to form prolongations d^3 of the seats for the elevator-sill beneath the inner cross-girts of the elevator-frame, that said girts may be bolted through 50 the sills to such offsets, as presently explained.

As in the before-mentioned application, the front platform-sill and the finger-bar attached thereto are likewise overlapped by a tubular bar E of rolled or forged iron, also rectangular in cross-section, which extends therefrom a sufficient distance to constitute the front sill of the elevator-frame. The rear elevator-sill is in line with the rear platform-sill; but the front elevator-sill usually flares somewhat 55 from the platform-sill, to which it is attached through the finger-bar, to give more space for the main wheel and binding attachment. Spacing-brackets are interposed between the front elevator-sill and finger-bar where they 60 overlap, in order to provide a space for the play of the sway-bar, where such bar is located beneath the A-frame of the elevator, or to 65

block up the elevator-base frame, which is also the gear-frame, to a higher level than the platform, and this in the present construction is the reason why such brackets are employed between the rear sills, as previously stated, although the sway-bar does not or need not pass between said rear sills, to wit, to bring the rear sill into its proper relation with the front sill. 75

F represents chairs such as employed in the Baker and Pridmore construction interposed between the elevator-sills and the cross-girts, of which latter four are shown, the innermost girt G in the angle at the foot of the elevator, then the two girts H H' , constituting the lateral bars of the wheel-frame, and, finally, the outer girt I at the stubble end of the machine; but of course the number depends 80 to some extent upon the type of machine or style of binder to be carried. The angle-iron finger-bar, the front elevator-sill, and the cross-girts are secured together in essentially the same way as heretofore; but as the wooden rear platform-sill is now dispensed with and spacing brackets or blocks employed between the two square bar rear sills the rear ends of the two inner girts are now secured by bolts passing through girt, chair, elevator-sill, and 85 offset from the respective underlying spacing-block, while the sills themselves are united by bolts passing through each and through the intermediate block. 90

The front and rear guides for the platform-apron are connected near the delivery end 95 by a cross-beam K , upon which is fixed a metal bridle K' , having guideways k for the play of a block K^2 lengthwise of the platform. From this block a spindle k' passes through 100 the bridge connecting the two arms of the bridle, and a spring k^2 , coiled around the spindle and resting at one end against the bridge and at the other against a collar or nut k^3 , secured to the end of the spindle, tends to 105 constantly force or draw the block toward the divider. Brace-rods K^3 , rigidly secured to said block, flare outward therefrom toward 110 and are rigidly secured to the bearing-boxes k^4 for the gudgeons k^5 of the idle-roller K^4 of 115 the platform-apron, and these bearings have flanges k^6 , sliding in ways formed in the divider ends of the apron-guides. Thus the idle-roller is constantly forced outward toward the 120 divider, keeping the apron taut.

The inner or non-adjustable roller L for the platform-apron has its rear gudgeon l supported in a long sleeve-bearing l' , that extends from the vertical plank C^2 rearwardly 125 through the inner elevator strut or board, and is there secured by means of an integral bracket plate or flange L' , seated upon, embracing, and bolted to the metal rear sill, and also independently bolted to the foot of said elevator-strut and serving to secure it to said sill. Outside of the bracket it is expected 130 that the gudgeon will receive a sprocket-wheel or pinion, whereby it may be driven. The rear elevator-struts are further braced by

means of an angle-iron bracket M, which sits upon the rear platform-sill at and rises vertically from the foot of the inner strut, which is herein shown as forming a rear board to the elevator after being suitably bolted to said strut and to the bracket-plate, which secures it to the rear sill, then extends horizontally a short distance toward the stubble side in order to form a seat to receive and support the seat-plank M', then passing at a slight upward incline toward said stubble side, is again bolted to the inner strut, and finally to the outer strut, making a very light and strong brace and subserving two functions.

As practically the whole platform-frame is of metal, it becomes necessary to modify the means whereby the divider and the grain-wheel are supported. The divider-girt, it has already been explained, extends obliquely forward, and, as usual, is in a horizontal position. It has been noticed that it is blocked up from the rear sill by means of a spacing-bracket. This is not absolutely necessary, but is adopted in order to raise it above the level of the upper ply of the platform apron or carrier, thus allowing the end of the latter to extend beneath or be carried beneath by the action of the tightener upon its movable roller, so as to exclude the possibility of grain dropping between. It follows of course that the forward end of the girt will be correspondingly raised above the finger-bar, the provision for which will be directly stated. It is then continued beyond the finger-bar to practically the extreme point of the divider, where a shoe N, capping and covering its open end, is bolted to it, from which the inclined dividing-board N' extends upwardly, outwardly, and rearwardly. A second or false shoe N² is bolted to the divider-girt somewhat to the rear of the divider-shoe, and is formed with a socket n, into which the point of the outer guard-finger n' enters, partly to insure a clean division of the grain and partly to brace the finger-bar and divider-girt.

A metal upright O is bolted to the divider-girt immediately above the finger-bar and has an offset o sitting over said girt and secured by a cross-bolt to make the connection more certain, and beneath it is bent laterally and formed with a seat, which rests upon said finger-bar, and a flange o', depending along the vertical flange of said bar and embracing it by a snug o² at the bottom, and secured to said flange by horizontal bolts; while at its upper end it bends obliquely at o³, so as to be secured to and aid in supporting the divider-board.

The grain wheel P turns upon a stub-axle p, projecting from a sliding block p', sliding in ways in a rack-standard P', and adjusted by means of a lever P² and a dog controlled therefrom. Such rack-standard and the accompanying means of adjustment have been used heretofore upon machines introduced into the market by the McCormick Harvest-

ing Machine Company, with these exceptions, that the standard is now bolted to the tubular divider-girt, being provided with an oblique ledge p², that complements the obliquity of the divider-girt, so as to bring the grain-wheel parallel with the line of travel, this ledge having snugs which sit over and grasp said girt, and that the fastenings being completed by bolts it extends up and is deflected obliquely outward at the top, as at p³, so as to be bolted to the rear end of the divider-board and further secure it.

To protect the grain-wheel from ordinary injuries, a fender-bar R is bolted at r to the grain end of the rear platform-sill, then is bent outward and carried forward outside of said sill until immediately in front of the wheel it reaches the just-mentioned upright, which connects the finger-bar, divider-girt, and grain-board, when it passes through lateral snugs r', formed integrally with the foot of said upright at and just above the grain end of the front sill and finger-bar, thence is bent obliquely inward until it reaches the front end of the divider-girt, to which it is secured, preferably, by the same bolt that unites the latter to the divider-shoe.

We claim as our invention—

1. The combination, substantially as hereinbefore set forth, of the rear platform-sill formed of metal and tubular in cross-section, the rear elevator-sill likewise formed, the spacing blocks or brackets interposed between the two and having offset bolts uniting the two and passing through the interposed spacing-blocks, cross-girts superposed on the rear elevator-sill, and bolts passing through said cross-girts, said elevator-sill, and offsets from the spacing-blocks.

2. The combination, substantially as hereinbefore set forth, with the tubular rear platform-sill, of the wooden bar bolted to its front or inner side, whereby the bottom boards may be secured.

3. The combination, substantially as hereinbefore set forth, with the tubular rear platform-sill rectangular in cross-section, of the wooden bar bolted to its front or inner face, the vertical plank in advance of said bar and supporting the rear guide-bar for the platform-apron, and the hinged lid bridging the space between said plank and the wooden bar to form a tool-box.

4. The combination, substantially as hereinbefore set forth, to form an apron-tightener, of the cross-beam extending from front to rear guide-bar, the bridle-piece supported centrally on said cross-beam, the block sliding in ways in said bridle-piece, the spindle passing through the block and through the bridge which unites the arms of the bridle-piece, the spring coiled about said spindle outside of the bridge and tending to draw the sliding block in the direction of the movable roller, the brace-bars bolted to said sliding block and extending obliquely therefrom to the bearing-boxes of said movable roller, and the

ways for said boxes in the outer ends of the guide-bars.

5. The combination, substantially as hereinbefore set forth, with the metal rear sill 5 and metal divider-girt, both being tubular and rectangular in cross-section, of the fender-bar bolted to the outer end of the rear sill and passing around outside of the grain-wheel to the front end of the divider-girt, to 10 which it is bolted, and the lateral snugs r' , embracing said fender and located at the grain side of the front sill, whereby it is supported in advance of the grain-wheel.

6. The combination, substantially as hereinbefore set forth, of the square pipe rear 15 platform-sill, the square pipe divider-girt bolted thereto, the angle-iron finger-bar rigidly secured to said girt, the divider-shoe secured to the extreme front end of said girt 20 and capping or closing it, and the divider-board rising obliquely from said shoe and sustained at its rear by a brace or support from the girt.

7. The combination, substantially as hereinbefore set forth, of the rear sill, the finger-bar, the platform-apron, and the divider-girt blocked up from said sill and finger-bar to admit the outer end of said apron beneath.

8. The combination, substantially as hereinbefore set forth, of the square pipe rear 30 platform-sill, the square pipe divider-girt, the interposed block, the angle-iron finger-bar, a rigid connection between said finger-bar and the girt serving to block the latter up from the former, and the platform-apron having 35 its upper ply below said girt, whereby its outer end may extend therebeneath.

9. The combination, substantially as hereinbefore set forth, of the square pipe rear platform-sill, the square pipe divider-girt, the interposed block, the angle-iron finger-bar, a rigid connection between said finger-bar and the girt serving to block the latter up from the former, the platform-apron having its upper ply below said girt, the yielding roller 45 at the outer end of said apron, and the tightener tending to carry said roller beneath the divider-girt.

10. The combination, substantially as hereinbefore set forth, of the rear platform-sill 50 formed of metal, tubular and rectangular in

cross-section, the divider-girt, the spacing block interposed between the two, and the bolts uniting them, the angle-iron finger-bar, the upright bolted to said finger-bar and again to the girt, the divider-shoe to which the front end of the girt is bolted, and the divider-board rising rearwardly therefrom and bolted to said upright.

11. The combination, substantially as hereinbefore set forth, of the rear platform-sill formed of metal, tubular and rectangular in cross-section, the divider-girt, the spacing block interposed between the two, and the bolts uniting them, the angle-iron finger-bar, 60 the upright bolted to said finger-bar and again to the girt, the divider-shoe to which the front end of the girt is bolted, the divider-board rising rearwardly therefrom and bolted to said upright, and the false shoe in rear of 65 the divider-shoe having a socket taking over the point of the outside guard-finger.

12. The combination, substantially as hereinbefore set forth, with the oblique divider-girt, of the rack-standard for the support of 75 the grain-wheel, having an oblique ledge whereby it is bolted to said girt, and an outwardly overhead flaring extension bolted to the rear end of the divider-board.

13. The combination, substantially as hereinbefore set forth, with the rear elevator-struts and the seat-plank, of the angle-iron brace-bar or bracket seated upon the rear sill and united thereto and to the foot of the inside strut, thence rising vertically to the 85 height of the seat-plank, there formed with a horizontal seat to receive the seat-plank, and thence extending outwardly and bolted in succession to the inner strut and the outer strut.

14. The combination, substantially as hereinbefore set forth, with a square pipe rear platform-sill, and with the inner platform-roller, of the bracket-plate bolted to said sill and also to the inner elevator-strut, and provided with a long sleeve-bearing for the reception of the gudgeon of said roller.
